UNITED STATES PATENT OFFICE.

MICHEAL E. TOEPEL, FRANK B. WIDMAYER, AND ADOLPH POTDEVIN, OF NEW YORK, N. Y.

OIL-ENGINE.

SPECIFICATION forming part of Letters Patent No. 682,822, dated September 17, 1901.

Application filed August 31, 1900. Serial No. 28,654. (No model.)

To all whom it may concern:

Be it known that we, MICHEAL E. TOEPEL, FRANK B. WIDMAYER, and ADOLPH POTDEVIN, citizens of the United States, and residents of the city of New York, in the counties of New York and Kings and State of New York, have invented a certain new and useful Oil-Engine, of which the following is a specification.

10 **Our invention relates to internal-combustion engines.**

The object of our invention is to secure a simple, compact, and durable engine and one particularly suited for use as a motor for 15 cycles or other vehicles.

Our invention consists in an improved bearing for the fly-wheel of the engine, the object being to secure a bearing of good length well adapted to take up the thrust of the 20 piston, while at the same time keeping the lateral dimensions of the motor down to a minimum and making it possible to dispense with the usual projecting shaft in one face of the crank-case, so that said face may be free 25 from the usual projecting hub or bearing for such shaft.

Another part of our invention relates to the manner of mounting a cam-disk which is adapted to secure a movement of the valve-operating rod for each two whole revolutions 30 of the crank without employing the reducing-gear which is ordinarily used in engines of this class to operate the exhaust-valve once in each cycle.

35 To these ends our invention consists in the construction and the combination of devices hereinafter described in connection with the accompanying drawings and then specified in the claims.

40 Figure 1 is a vertical section of a motor embodying our invention. Fig. 2 is a front elevation showing the valve-operating mechanism within the crank-chamber in dotted lines and cooling-ring for the cylinder in partial section. Fig. 3 is a face view of the cam-disk which actuates the valve push-rod detached. Fig. 4 is a side view, and Fig. 5 a plan view, of the dog which rides in the groove of the cam-disk.

1 indicates the engine-cylinder, 2 the piston, and 3 the connecting-rod, suitably pinned to the piston. 50

5 is the admission-valve rod, and 4 the exhaust-valve rod, both of which valves are normally seated by the action of springs surrounding the rods. 55

6 is the operating push-rod, which acts to open the exhaust-valve and which in the usual form of gasoline-engines of the four-cycle type is acted upon by a cam connected with the motor-shaft or crank-shaft by a reducing-gear, so that the valve shall be opened once in two revolutions of the crank-shaft. 60

7 is the crank-chamber, made in two parts bolted together and fitted together by a joint, 65 (indicated at 8.)

Each part of the casing is provided with an internal boss or projection 9, as shown, which forms an extended interior bearing for the shaft of the machine. The fly-wheel on the 70 machine is composed of the two disks or wheels 10, each of which is provided with a hub, as shown, preferably cast in one piece with it, said hubs constituting the shaft for the motor and having their bearings within 75 the internally-projecting bosses projecting inwardly from the shell 7. To extend the shaft of the machine outside of the casing for the purpose of communicating motion or for operating upon any parts, a rod 14 may be secured within the hollow hub of one of the fly-wheels 10, if desired. 80

3 is a connecting-rod connecting the piston 2 with the fly-wheels by means of a wrist-pin or bolt 11, extending through the fly-wheels, 85 as shown, and provided with a sleeve or bushing 13, which fits the opening in the head of the rod 3 and has a rotary bearing in the fly-wheels, as indicated. Preferably the sleeve is capable of turning within the head of the 90 connecting-rod. The inner faces of the fly-wheels are brought as closely together as practicable, so that by the construction shown the connecting-bearings between the fly-wheels and connecting-rod so far as possible overhang the bearings for the shaft of the machine. The purpose of this is not only to secure 95 strength and durability in the bearings, but

also to bring the lateral dimensions of the motor within as small a compass as possible. It will be seen also that the hubs of the fly-wheels being formed in one piece with them and extended out sufficiently to form practically a shaft for the motor, an extended bearing may be provided by bringing the inner faces of the wheels into close proximity and into line with the thrust of the connecting-rod. Thus the device is adapted to take up the heavy thrust of the explosion. It will also be seen that the outer faces of the halves of the crank-shell are smooth or flush and free from the usual projection on the line of the shaft of the engine. In other words, our machine has the bearings for its main shaft entirely inside of the crank case or shell, thus further adapting the machine for use as a bicycle-motor or in other situations where it is desired to use a machine of small lateral compass without projecting parts and to have bearings which shall be strong and durable and adapted to take up the heavy thrust of the explosions.

25 The exhaust-valve push-rod is operated from a cam-disk 15, set into the face of one of the fly-wheels and secured in position therein in any suitable manner. In fitting this cam-disk the line X thereon must be in line with the crank-pin. 16 is a curved dog which works in the double groove shown in the face of the cam-disk 15 and which is connected with the push-rod 6 in any suitable manner—as, for instance, by a pin 17, which engages the head 18 of said push-rod. The head 18 works up and down in suitable guides 19 on the inner face of one-half of the crank-chamber. The cam-groove is a double groove, the two parts of which meet on one side, as shown.

30 The inner groove is practically a by-pass groove for the dog, in which said dog rides during that revolution of the crank in which the piston on its outward movement draws in a fresh firing charge and on its backward movement compresses said charge and makes the same ready for firing. The dog is shown in Fig. 2 in the position which it occupies at the end of the outward movement of the piston, by which a fresh charge is drawn into

35 the cylinder. Assuming that the cycle of actions begins at this point, the changing position of the dog in the groove would be as indicated by the dotted line, Fig. 3, provided with arrow-heads at intervals, assuming that the revolution of the disk is in the direction of the arrow 20. On the completion of the compression the dog occupies the position indicated by the dotted lines at 16². The charge is then fired, and the forward end of

40 the curved dog at the beginning of the outward movement of the piston under the impulse enters the outer groove and at the end of the impulse occupies the position 16³ in said groove, ready for being moved outward

further to open the exhaust-valve and keep it opened during the next half-revolution of the crank as the piston moves backward. At the end of this half-revolution the dog occupies in the cam-groove the position 16⁴ and on the next outward movement is guided into the inner portion of the groove by the shoulder 21, so as to close the exhaust and cause a fresh charge to be drawn into the cylinder, the cycle of actions being completed when the piston completes its outward movement and the dog reassumes the original position. (Indicated in Fig. 2.) As will be seen, the inner groove of the cam-disk forms, in effect, a by-pass groove, whereby the exhaust-valve mechanism or push-rod is rendered inactive during one whole revolution of the crank.

We claim as our invention—

1. In an internal-combustion motor the combination with the fly-wheel having a recess in its face, of a valve-operating cam-disk fastened within said recess.

2. In an internal-combustion motor a valve-operating cam-disk having a double cam-groove adapted to operate the valve once for each two whole revolutions of the crank-shaft combined with a fly-wheel having a recess in its face and means for securing said cam-disk within said recess.

3. In an internal-combustion motor, the combination with the two-part crank casing or shell each having a hollow internal boss or projection adapted to form a bearing for the shaft of the motor, of a two-part fly-wheel and a motor-shaft composed of the hubs of said fly-wheels formed in one piece with them and journaled within the said hollow bosses or projections, as and for the purpose described.

4. In an internal-combustion motor of the inclosed-crank type, bearings for the motor-shaft located entirely inside of the crank case or shell and consisting of internal bosses or projections projecting from the inside of the crank case or shell and within which are journaled the shaft of the motor consisting of the hub or hubs of the motor fly-wheels.

5. In an internal-combustion motor the combination of a pair of fly-wheels and a connecting-rod connecting thereto by bearings which overhang the shaft-bearings of the motor, and a motor-shaft consisting of the hubs of said fly-wheels formed in one piece therewith and journaled in internally-projecting hollow bosses forming a part of the crank-casing, as and for the purpose described.

6. In an internal-combustion motor, a motor-shaft consisting of hubs, of the fly-wheels formed in one piece with them and journaled in hollow bosses projecting inwardly from the casing or shell of the machine and all constructed as described so that the bearings of the motor-shaft shall be located entirely within the crank case or shell leaving the outer face of said shell flush or smooth.

7. In a motor of the inclosed-crank type, a
crank-shell having hollow internally-project-
ing hubs or bosses and flush or smooth exte-
rior surfaces combined with the fly wheel or
5 wheels whose shaft is mounted in said bear-
ings and with the bearing-surfaces entirely
inside of the crank case or shell, as and for
the purpose set forth.

Signed at New York, in the county of New

York and State of New York, this 29th day of 10
August, A. D. 1900.
